UNITED STATES PATENT OFFICE.

ARCHIBALD K. ALLEN AND CLARENCE A. ALLEN, OF SEATTLE, WASHINGTON.

DESIGN FOR A TIRE.

59,806.

Specification for Design.

Patented Nov. 29, 1921.

Application filed January 19, 1921. Serial No. 438,456. Term of patent 3½ years.

To all whom it may concern:

Be it known that we, ARCHIBALD K. ALLEN and CLARENCE A. ALLEN, citizens of the United States, residing at the city of Seattle, in the county of King and State of Washington, have invented a new, original, and ornamental Design for Tires, of which the following is a specification, reference being had to the accompanying drawing, forming part thereof.

Figure 1 is a plan view of a tire, showing our new design.

Fig. 2 is a sectional view on the line 2—2 of Fig. 1.

We claim:

The ornamental design for a tire, as shown.

ARCHIBALD K. ALLEN.
CLARENCE A. ALLEN.
